UNITED STATES PATENT OFFICE.

JAMES L. LAYTON AND GEORGE P. WALLACE, OF TACOMA, WASHINGTON.

BLOWTORCH.

1,412,689.

Specification of Letters Patent. Patented Apr. 11, 1922.

Application filed October 21, 1920. Serial No. 418,614.

To all whom it may concern:

Be it known that we, JAMES L. LAYTON and GEORGE P. WALLACE, citizens of the United States, residing at Tacoma, in the county of Pierce and State of Washington, have invented certain new and useful Improvements in Blowtorches; and we do declare the following to be a full, clear, and exact description of the invention, such as 10 will enable others skilled in the art to which it appertains to make and use the same.

This invention relates broadly to improvements in blow-torches, and has more particular reference to a novel device to be 15 installed in the mixing chamber of a blow-torch which will obtain an intimate mixture of the oil and air and will thus produce an efficient combustible mixture which is better than the ordinary mixture produced.

20 The principal object of the invention is to generally improve upon and simplify the construction of blow-torches and the like including mixing devices.

Another object of the invention is to provide 25 an improved mixing device for torches and the like comprising a small disk-like member provided with peripheral angularly disposed blades which are twisted laterally with respect to the body portion so as to 30 provide spaces between them to permit the passage of a portion of the fuel therethrough, this disk-like member being loosely mounted in the mixing chamber and solely rotated and held in the proper position by the fuel 35 which is forced against it.

A further object of the invention is to provide a novel mixing device of the above mentioned type which is provided with a centrally disposed escape port arranged in 40 parallelism with the air inlet passage and discharge passage of the device, whereby the air will pass through it and cause the mixture to be more effectively expelled from the discharge passage.

45 Other objects and advantages of the invention will be apparent during the course of the following description.

In the accompanying drawings forming a part of this specification and in which like 50 numerals are employed to designate like parts throughout the same:

Figure 1 is an elevational view of a torch constructed in accordance with my invention.

55 Figure 2 is a central longitudinal sectional view, with parts in elevation, showing the

internal construction and specific mixing device more clearly.

Figure 3 is a sectional view of one of the 60 details of the device.

Figure 4 is a detail elevational view of my improved mixing device.

In carrying out the invention, we employ a body member which is provided with a mixing chamber having fuel inlet and outlet 65 means communicating therewith, there being a novel mixing member of disk-like formation loosely mounted in this mixing chamber, the same being rotated and solely held in its proper place by means of the fuel under pressure which is directed against it. 70

Referring to the drawings, wherein the preferred embodiment of my invention is clearly disclosed, it will be seen that the numeral 1 designates, as a whole, a body member which is provided with a mixing chamber 2 wherein the air and oil are intimately mixed before passage out of this chamber. Communicating with this chamber at one end, are fuel feed pipes 3 and 4, air being 80 fed through the first named pipe and oil or kerosene being fed through the pipe 4. Also communicating with this chamber and extending from the opposite end thereof is a suitable discharge passage 5. Before going 85 into the description of my improved mixing device, we will first set forth the specific construction and arrangement of the body member 1. This body member is preferably made up of a centrally bored element 6 provided with screw-threaded portions 7 and 8, a screw-cap 9 which is fitted onto the extension 7, thus forming the aforesaid chamber 2 between its closed end and the adjacent end of the element 6. The closed end 90 of the screw-cap 9 is provided with a plurality of passages 10 with which the fuel pipes 3 and 4 communicate. It may be stated at this point that it is desirable to equip the oil supply pipe 4 with a suitable check valve 100

11. Any suitable means, for instance a nipple 12 and a pipe 13 may be connected to the portion 8 of the element 6 for the purpose of distributing the mixed fuel to a suitable part such as a burner head or a nozzle which 105 ever may be connected to the end of the pipe 13. Now by referring back to the element 6, it will be seen that we form a conical socket 14 in the end of this element which communicates with the mixing chamber 2. This 110 socket constitutes what may well be termed a seat and this seat is adapted to receive and

support my improved mixing device, designated, as a whole, by the numeral 15. The mixing device 15 is preferably in the form of a metal disk which has its periphery split 5 to provide a plurality of blades 16 which are angularly bent with respect thereto and are twisted laterally to provide spaces between them which permits passage of a portion of the fuel therethrough and into the discharge 10 passage 5. Attention is directed to the fact that this mixing member 15 is loosely mounted within the chamber and rests against the conical seat 14. There is no special means employed to retain the mixing member in 15 position and it is retained in position and solely rotated by means of the fuel under pressure which is directed against it. Careful examination of the location of the air pipe 3 will disclose the fact that it is located 20 at approximately the center of the screw-cap 9 so that the air issuing therefrom will contact the imperforate portion of the disk 15 and retain the latter in place. Furthermore, since the disk 15 is provided with a 25 centrally located fuel escape port 17, it will be seen that a great portion of the air issuing from the pipe 3 will effectively carry the mixed fuel through this opening 17 and will also effectively expel the fuel from the discharge passage 5 and give it sufficient velocity 30 to cause it to reach the burner head or nozzle on the end of the distributing pipe 13. Attention is further directed to the fact that the member 6 and the screw-cap 9 are 35 both provided with flat face exterior portions to permit a wrench or the like to effectively engage these portions to disconnect the parts of the body for cleaning and repairing.

40 The operation of the device is as follows: Air under pressure is fed through the pipe 3 into the chamber 2 while oil or other similar fuel, likewise under slight pressure, is supplied to this chamber 2 through the pipe 45 4, the passage of this part of the fuel being controlled by means of the valve 11. Since the air pipe is centrally located, the air issuing therefrom will be forced against the imperforate portion of the disk 15 and retain 50 the latter in position in the seat 14 and a portion of this air in conjunction with the oil which is directed against the blades 16 will cause automatic rotation of this member 15 and in so doing will bring about a complete 55 and intimate mixture of air and oil and will form a very efficient combustible fuel vapor, the greater portion of which is forced through the central aperture 13 in the member 15 by the swift current of air which passes there- 60 through. The peculiar construction of the angular blades 16 of the member 15 provides spaces between them through which a portion of the oil will seep and gain entrance to the discharge passage 5. As the space between these blades is somewhat limited, the 65

amount of oil passing therethrough will be restricted so as to insure that the proper proportion of air and oil will enter the discharge passage 5. The velocity at which the air passes through the central port 17 in the 70 member 15 is sufficient to effectively carry the thoroughly mixed fuel through the parts 12 and 13 to the burner head or nozzle on the end of the latter and a perfect blue flame will be produced.

75 From the foregoing description, it will be seen that we have devised an extremely effective mixing device for installation in the mixing chamber of a torch or the like which will insure an intimate mixture of the air 80 and oil or other fuel, one which is extremely simple in construction and inexpensive to manufacture, and one which may be easily replaced whenever desired or necessary due to the easy disconnection of the parts of the 85 body in which it is arranged. By loosely mounting this mixing device in the chamber and solely rotating it and retaining it in position against its seat by the fuel under pressure which is directed against it, a novel 90 device has been produced. By arranging the air pipe at a point centrally of the screw-cap which supports it, the current of air issuing therefrom not only effectively retains the mixing device in position, but a portion of 95 this air passes through the central opening in the mixing chamber and insures an effective expulsion of the mixed fuel from the discharge passage and gives the fuel sufficient velocity to insure that it will reach the 100 burner head or nozzle on the end of the delivery member 13. These and other advantages have, no doubt, become apparent from the foregoing description and drawings.

105 While we have shown and described my improved mixing device as being used in connection with a blow-torch, we desire it to be understood that it may be equally well used in the mixing chambers of various other similar devices such as burners and the like.

110 A careful consideration of the foregoing description taken in connection with the accompanying drawings will enable persons skilled in the art to which the invention relates, to obtain a clear understanding of the 115 same, therefore, further description is deemed unnecessary.

120 Since advantageous results may be obtained with the construction and arrangement herein described and shown, this construction and arrangement is taken as the preferred embodiment of my invention. However, it is to be understood that various minor changes in the shape, size, and arrangement of parts may be resorted to so 125 long as they do not depart from the spirit of the invention or the scope of the subjoined claims.

130 We claim:

1. A device of the class described compris-

- ing a body including a chamber having a fuel inlet and an outlet communicating with the chamber, a separate and independent mixing member arranged for rotation in said chamber the same being provided with a plurality of angular mixing blades and a restricted port registering with said outlet. 2. A device of the class described comprising a body including a chamber having fuel inlets and an outlet, and a member for mixing the fuel rotatable in said chamber, said member being a centrally apertured disk, the periphery of which is slotted to provide a series of blades which are angularly bent and twisted laterally to provide passages between them for the fuel. 3. A fuel mixing device comprising a body having a chamber provided with a fuel inlet and an outlet, and a loosely mounted mixing member arranged in the chamber, being rotated and solely held against one wall of the chamber by the fuel and air which is directed against it.
4. A fuel mixing device comprising a body having a fuel mixing chamber provided with feed and discharge means, and being also provided with a socket communicating with said discharge means, and a disk-like mixing member loosely mounted in said socket, being provided with angular peripheral blades and being solely rotated and held in the socket by the fuel and air which is directed against it.
5. The structure set forth in claim 4, said disk-like member being provided with a relatively small central fuel escape opening communicating with said discharge means.
- In testimony whereof we have hereunto set our hands.

JAMES L. LAYTON.
GEORGE P. WALLACE.
